UNITED STATES PATENT OFFICE

2,515,226

SEPARABLE PROJECTOR CATCHER

Philip R. Horwitz, Leominster, Mass., assignor
to Paramount Manufacturing Company, Leominster, Mass., a corporation of Massachusetts

Application July 23, 1948, Serial No. 40,250

6 Claims. (Cl. 273—97)

1

The present invention relates to a toy in which a return ball or the like has its elastic cord attached to a container in which the ball is to be caught. Such toys are commonly used by children at play, and considerable skill is required and developed in the child in its use.

The present invention relates to an improvement in such a toy and more particularly to the improvement in construction and manufacture, as will be more fully explained in the specification as set forth below describing an embodiment of the same when taken in connection with the drawings in which:

Figure 1 shows the toy in elevation with the upper part in section.

Figure 2 is a plane view substantially looking down on Figure 1, and,

Figure 3 is a perspective fragmentary section of a detail of the invention.

Figure 4 shows an exploded view partly in section of the base of the cup and part of the handle, and,

Figure 5 shows a further exploded view of fragments of the handle and base of the cup taken on the line 5—5 of Figure 4.

The toy, as illustrated in the drawings, is preferably molded from plastic such as polystyrene, cellulose acetate, or some other common plastic molding material. The toy is comprised in general of four parts, the bell shaped receptacle, the handle 2, return ball 3, and the rubber cord 4. The bell shaped receptacle 1 may be molded if desired with a smooth rounded lip 5 and a chamber or cone narrowing down to the handle end, 6. The open cone or cup is rounded at the end as indicated at 7. The small end of the receptacle is rounded at the end of the conical wall and provided with a flat end 7, through which a substantially circular hole is made which is recessed at diametrically opposite sides in slots 8 and 9. In the flat end surface on the inside of the cone adjacent the recessed slots are inwardly projected bosses or pins 10 and 11 diametrically opposite each other. The handle 2 is provided with an end which engages the hole and slots in the receptacle. This handle is formed with an outwardly extended flange 12 from the flat surface of which a circular collar 13 projects centrally with respect to the axis of the handle. This collar 13 is just slightly smaller than the rounded hole 14 in the end of the receptacle and fits into the hole and may be readily turned in it. The collar 13 merges into an anchor-like member 15 which projects from the flat face of the collar and is provided with two arms 16 and

2

17 diametrically opposite one another extending from a rounded central section 18 of the member 15. The rounded section 18 has an axis which is perpendicular to the longitudinal axis of the handle 2. A hole 19 is provided through the rounded section 18, parallel to the axis and through this hole the cord 4 of the return ball is tied.

In the flat end of the cup the wall thickness 10 adjacent the hole 14 varies in thickness from a thicker section near the bosses or pins 10 and 11 to a thinner section in the regions marked 20 and 21. This tapering may be noted both in Figures 4 and 5. The spacing between the lower 15 surface of the arms 16 and 17 and the top surface of the flange 12 is such that when the arms are inserted in the slots 8 and 9 sufficient clearance is obtained so that the handle may be rotated away from the position of the pins. The wall 20 adjacent the slot and the hole in this position 17 is such that a sliding fit is provided. As the handle, however, is turned further, the increasing thickness of the wall will bring about a binding between the handle and the wall 25 of the cup until the arms reach the position of the pins 10 and 11 whereupon they can be turned no further.

In assembly the handle is inserted through the hole of the receptacle after the return ball cord has been tied, with the projecting arm 16 and 30 17 aligned in the slots 8 and 9 in the end of the cone. The handle is then turned about its axis with respect to the receptacle until the arms 16 and 17 bind against the flat surface of the cap 35 beside the hole 14.

It is a simple matter to replace the cord by a new cord when this is desired. All that must be done is to turn the handle as viewed in Figure 40 2 of the drawing in a clockwise direction until the arms of the handle are aligned with the slots 8 and 9 whereupon the handle may be drawn clear of the cup or cone and a new return cord easily attached.

I claim:

45 1. A toy of the type described comprising a plastic cup having a flat base section with a round hole axially positioned with respect to the cup and slots extending outwards from the sides of the hole in diametrically opposite positions 50 with respect to said hole, the wall at either side of the slots of the hole being tapered in thickness in the same rotational direction, a handle having a flanged end with a cylindrical collar fitting into said hole and outwardly extending arms 55 diametrically positioned with respect to the col-

lar and spaced above the flanged end the thickness of the wall in the thinner portion of the tapered section, and means provided at the end of the handle normally within the cup to which a return ball cord may be tied.

2. A toy of the type described comprising a plastic cup having a flat base section with a round hole axially positioned with respect to the cup and slots extending outwards from the side of the hole in diametrically opposite positions with respect to said hole, the wall at either side of the slots of the hole being tapered in thickness in the same rotational direction, a handle having a flanged end with a cylindrical collar fitting into said hole and outwardly extending arms diametrically positioned with respect to the collar and spaced above the flanged end the thickness of the wall in the thinner portion of the tapered section, and means provided at the end of the handle normally within the cup to which a return ball cord may be tied.

3. A toy of the type described comprising a plastic cup having a flat base section with a round hole axially positioned with respect to the cup and slots extending outwards from the side of the hole in diametrically opposite positions with respect to said hole, the wall at either side of the slots of the hole being tapered in thickness in the same rotational direction, a handle having a flanged end with a cylindrical collar fitting into said hole and outwardly extending arms diametrically positioned with respect to the collar and spaced above the flanged end the thickness of the wall in the thinner portion of the tapered section, a boss on the inner surface of the flat base section adjacent the hole in the thicker portion of the tapered wall, and means provided at the end of the handle normally within the cup to which a return ball cord may be tied.

4. A toy of the type described comprising a plastic cup having a flat base section with a round hole axially positioned with respect to the cup and slots extending outwards from the side of the hole in diametrically opposite positions with respect to said hole, the wall at either side of the slots of the hole being tapered in thickness in the same rotational direction, a handle having a flanged end with a cylindrical collar fitting into said hole and outwardly extending arms diametrically positioned with respect to the collar and spaced above the flanged end the thickness of the wall in the thinner portion of the tapered section, bosses diametrically opposite at the edges of the hole on the inner face thereof in the thicker portion of the tapered wall, and means provided at the end of the handle normally within the cup to which a return ball cord may be tied.

4. A toy of the type described comprising a plastic cup having a flat base section with a round hole axially positioned with respect to the

cup and slots extending outwards from the sides of the hole in diametrically opposite positions with respect to said hole, the wall at either side of the slots of the hole being tapered in thickness in the same rotational direction, a handle having a flanged end with a cylindrical collar fitting into said hole and outwardly extending arms diametrically positioned with respect to the collar and spaced above the flanged end the thickness of the wall in the thinner portion of the tapered section, and means provided at the end of the handle normally within the cup to which a return ball cord may be tied, said means comprising a projecting boss at the end of the handle having a hole therethrough to which the return ball cord is tied.

5. A toy of the type described comprising a cup having a hole in the base thereof, a handle having an end fitting into said hole, means in part provided at the end of the cup and at the end of the handle for rotating the handle into locking position in said cup and means provided at the end of the handle within the cup to which a return ball cord may be tied.

6. A toy of the type described comprising a plastic cup having an opening in the base thereof, a handle having one end fitting into the open end of the cup, closing said opening, means in part on the handle and in part on the cup base for removably attaching the handle to the cup, and means provided on the end of the handle within the cup to which a return ball cord may be tied.
